PROCESS OF PRODUCING THICK BUTT SHINGLES WITH SEALED EDGES

Clarence R. Eckert, Englewood, N. J., assignor to
The Barrett Company, New York, N. Y., a corporation of New Jersey

Original application August 14, 1926, Serial No.
129,132. Divided and this application October
10, 1931. Serial No. 568,057

4 Claims. (Cl. 91—68)

This invention relates to a process of making shingle elements, and more particularly to the manufacture of thick butt strip shingles having tabs disposed along one longitudinal edge 5 of the body portion thereof, the cut edges of the strip shingles being sealed by means of a suitable water-proof coating. This application is a division of application Serial No. 129,132, filed August 14, 1926, claiming a continuous process 0 for making thick butt shingles.

Thick butt shingle elements have heretofore been made chiefly by hand-dipping a granular surfaced coated felt base into a bath of molten asphalt or other bituminous material, the element 5 allowed to drain and then surfaced with granular material. This is an expensive and unsatisfactory manner of producing thick butt shingles since it involves time-consuming hand labor and waste of asphalt occasioned by the dipping operation.

In applicant's prior application, Serial No. 129,132, hereinabove referred to, a continuous process of making thick butt shingles is disclosed and claimed. This application is directed to the 5 novel procedure disclosed in the prior application permitting the sealing of all coated edges of the strip shingles with water-proofing material during the production thereof from a web of a width sufficient to produce a plurality of 10 strips which are subsequently cut into shingles, and this without transverse flexing or bending of the fibrous base with consequent disrupting and weakening of the base.

According to my prior application, a fibrous 5 foundation preferably the usual roofing felt, is first saturated with asphalt or other bituminous material, dried, and while moving in a horizontal direction, coated with asphalt on both sides. The top coating is then surfaced with granular material and mica dust applied to the base coating to render it non-cementitious. Thereafter the surfaced web is cut longitudinally into a plurality of strips, four in the embodiment of the invention disclosed. Each strip is cut so as to 10 provide tabs along one longitudinal edge thereof. The face of the spaced tabs and the cut edges are then coated with asphalt or other water-proofing material and granular material is applied to the coating to form a thick butt shingle, 15 the tab portions of which have a double coating and surfacing on the felt foundation whereas the body portion has but a single coating and surfacing on the felt foundation.

To permit the effective sealing of the forward 55 tab edges of the strip with coating material in

continuous processes of manufacturing the elements such as briefly described above, it is necessary to separate the contiguous strips formed in the longitudinal slitting of the starting web. If the strips are not separated the coating material applied to the surfaces of contiguous strips adheres to the faces thereof and does not effectively seal the longitudinal cut edges. Separating the strips by causing them to move apart from each other after the web is cut, involving 60 transverse movement of the cut strips with respect to the portions of the web from which they are cut, it has been found, weakens and tends to disrupt the felt base, seriously impairing the final product. 65

In accordance with this invention the strips formed by the longitudinal slitting operation are separated by passing alternate strips about guides so that they travel in the same longitudinal direction as the portions of the web from which they are cut but in a different horizontal plane from the plane of movement of the remaining strips formed in the cutting operation. Thus, if four strips are cut from a web and the strips be numbered 1 to 4 from right to left, viewing Fig. 3 of the drawing, strips 1 and 3, while traveling in the same longitudinal direction as the portions of the web or fabric from which they are cut, are caused to travel in a different horizontal plane and are consequently separated a distance equal to the width of the intervening strip. Separation of the strips in this manner gives ready and complete access to the cut edges of the strip in the succeeding coating and sealing operation. 70

Strips 2 and 4 may travel in the same horizontal plane as the starting web or may be elevated or depressed to travel in a different plane from that in which strips 1 and 3 travel. Thus, it will be noted that the individual strips are separated 75 while continuously moving in the same longitudinal direction as the portions of the starting web from which they are cut without moving the strips transversely of the longitudinal direction of movement of the corresponding portions of the starting web. Hence, the felt base is not subject 80 to strains and weakening influences occasioned by movement of a portion of the strip transversely to the longitudinal direction of movement of the remaining portion of the strip. 85

In the accompanying drawing illustrating one embodiment of this invention in which like reference characters refer to like parts—

Fig. 1 is a diagrammatic side elevation, partially in section, of the type of apparatus which 100

110

I have found satisfactory for carrying out my invention;

Fig. 2 is a diagrammatic plan view of the web as it travels through the apparatus;

5 Fig. 3 is a diagrammatic perspective view showing the cut web as it leaves the longitudinal cutters and indicating the path of movement of the cut strips resulting in the separation thereof;

Fig. 4 is a vertical section partly in elevation of 10 apparatus which may be employed for the application of the butt thickening coating to the strips;

Fig. 5 is a plan view of the apparatus of Fig. 4, showing the coating mechanism for two strips; and

15 Fig. 6 is a section, taken through one of the tabs, of the thick butt shingle of my invention.

Referring now to the drawing, a web A of roofing felt of the desired width is led through the saturating tank 5, where it may be impregnated 20 with a suitable water-proofing compound, such as asphalt or tar. The saturated web passes between the squeeze rolls 6 for removing excess saturant after which the web may pass over drying racks 7 for allowing the saturated web to 25 cool somewhat. The web is then fed through the coating rolls 8 and 9, by means of which a relatively thin coat of weather-proofing compound, such as tar or asphalt (usually of a higher melting point than that of the saturant), is applied to the impregnated sheet. While the coating 30 is still soft, the web passes under the hoppers 11 and 12 and around the rolls 13 and 14.

The hoppers 11 and 12 are of usual design, hopper 11 containing crushed slate, or other wear-resistant granular material, of any suitable color 35 or mixture of colors which may be showered upon the face of the coated web, thus surfacing the web. Hopper 12 contains mica dust which is fed to the rear surface of the web as it passes about 40 roller 13, thus rendering the rear surface of the web non-cementitious.

The web now passes over the cooling rolls 15 and 16 and over the idler roll 17 and between the platen roll 18 and the cutting roll 19. By 45 the installation of the desired cutting roll the finished shingle element may be made to take the form of a strip having rectangular tabs, or hexagonal tabs, or octagonal tabs or other desired shape. Such cutting practice is, in general, known to those skilled in the art, and it is thought, need not be dealt with more specifically here. After passing the cutting roll, the web A will appear as a plurality of strips 1, 2, 3, and 4 (Figs. 2 and 3). These strips pass through the 50 tab knocker 20 and splitter assembly 21 which, in the case of the type of shingle strip shown, removes the "cut outs" and splits the almost severed web into strips having shingle simulating tabs. (The specific details of this assembly are 55 described and claimed in U. S. Patent No. 1,744,473). Obviously, if octagonal or hexagonal shingles are being produced certain portions of the tab knocker and splitter assembly, such as the tab knocker itself, would be omitted.

65 The cut web, shown to the extreme left of Fig. 3, now passes on to conveyor bands 22 and 23. Strips 1 and 3 are carried by bands 22 in a downward direction while strips 2 and 4 are carried by bands 23 in an upward direction as 70 indicated in Fig. 1. Strips 1 and 3 are thus moved in the same longitudinal direction as the direction of movement of the portions of the web from which they are cut but in a different horizontal plane from that in which strips 2 and 4 are moved (see Figs. 1 and 3). Strips 2 and

4 also travel in the same longitudinal direction as the direction of movement of the portions of web A from which they are cut and pass over idler roll 65 while strips 1 and 3 pass over idler roll 64 to the tab or butt-thickening apparatus hereinafter described. Thus, the strips are separated without distortion to give ready access to the cut edges permitting effective sealing of the cut edges.

The strips 1, 2, 3 and 4 are now ready to have applied thereto the tab or butt-thickening coating of weather-resisting compound such as asphalt, tar, or other bituminous material. This is accomplished by means of an apparatus as shown in Figs. 4 and 5, and indicated generally in Fig. 1 by the reference numerals 24 and 25.

The coating apparatus of Figs. 4 and 5 involves a coating material tank 33 arranged to feed the coating material to a coating roll 34 having an enlarged portion 35 thereon. The flow of coating material from tank 33 upon the enlarged portion 35 of roll 34 is controlled by means of a gate 36. Enlarged portion 35 of roll 34 applies the coating 30 to the upper side of the tabs and to the edges thereof, while the strips are supported on plates 66, the coating material being supplied to the portion 35 of roll 34 slightly in excess of that needed to coat the upper surface of the tabs so that sufficient coating material will run over the edges of the tabs to coat them. Thus, the face of the tabs and the cut edges thereof are completely covered and sealed with bituminous coating material. If desired additional coating material may be applied to the cut edges by means of a pipe or hose arranged to discharge coating material onto the edges.

While the coating material is still soft and plastic the strips 1 and 3, and 2 and 4 pass under crushed slate hoppers 36, one for each strip, which shower crushed slate or other wear-resistant 1 material upon the coated portion of each strip. As shown in Fig. 1, the strips also pass over the rolls 41 which press the crushed slate into the plastic coating. The strips are then conducted over the cooling rolls 42 and over the timing rolls 43, projections upon the periphery of which engage in the notches between the tabs upon the strips. The cutters 44 are so synchronized with the timing rolls 43 that the strips are cut along a line of severance between the tabs 1 to form the finished shingle strips or elements 50, a section of which is shown in Fig. 6.

From Fig. 6 it will be noted that the element involves a felted fibrous foundation 51 which may be and preferably is the usual roofing felt. This 1 felt, as hereinabove described, is saturated with bituminous material and then the upper surface is completely coated with bituminous material as indicated at 52. If desired, the base of the felted foundation may be rendered non-cementitious by 1 dusting it with mica, indicated by the reference numeral 53. A layer of granular material 54 is partially embedded over the complete face of the bituminous coating 52. A second coating 55 of bituminous material extending about the cut 1 edges of the tab, thus sealing the edges, and over the tab portion only of the element, is then applied to the granular surfacing 54. Granular material 56 is then partially embedded in the bituminous coating 55.

By the expression "moving alternate strips in the same longitudinal direction as the portions of the base from which they are cut", used in the claims, is meant that the direction of movement of the strips after contiguous strips have 1

been separated either by depressing or elevating alternate strips is in the same longitudinal direction as the direction of movement of the web from which the strips were cut.

5 While the embodiment of the invention hereinabove described pertains to the manufacture of thick butt strip shingles, it will be understood that the invention is not confined thereto and is applicable to the treatment of fibrous and other 10 bases which are weakened or disrupted by moving a portion thereof transversely to the remaining portion.

I claim:

15 1. In the method of treating the edges of a plurality of strips produced from a single web which is weakened when a portion thereof is moved in the same plane transversely to the remaining portion, the improvement which involves cutting the web into a plurality of contiguous strips, and moving alternate strips in a different plane from that in which the remaining cut strips move, thus separating the contiguous edges of the cut strips a distance equal to the width of the intervening strips cut from the web.

20 2. The method of sealing the edges of contiguous strips of felt cut from a felt base which comprises moving a felt base, cutting said base into a plurality of contiguous strips, moving alternate strips in the same longitudinal direction as 25 the portions of the base from which they are cut and in a different plane from that in which the remaining strips travel, thus separating the cut edge of the strips a distance equal to the width of the strips between alternate strips when cut 30 and treating the cut edges of the strips with waterproofing material.

35 3. The method of sealing the edges of con-

tiguous strips of felt cut from a felt base which comprises moving a felt base in a horizontal plane, cutting said base into a plurality of contiguous strips, moving alternate strips in the same longitudinal direction as the portions of the base from which they are cut in a plane at an angle to the plane of movement of the felt base and then in a plane substantially parallel to the plane of movement of said base and the plane of movement of the remaining strips, thus separating the cut edges of the strips a distance equal to the width of the strips between alternate strips when cut and coating the cut edges of the strips with waterproofing material.

4. The method of making thick butt shingles having tabs disposed along one longitudinal edge which comprises continuously moving a felt web through a saturating bath, continuously coating with waterproofing material the upper surface of said web, continuously surfacing with granular material the coated face of said web, continuously cutting said web into strips each having tabs disposed along one longitudinal edge thereof, continuously separating said strips by moving alternate strips in the same longitudinal direction as 100 the portions of the base from which they are cut and in a plane different from the plane of movement of the remaining strips, thus separating the cut edges of the strips a distance equal to the width of the strips intervening alternate strips 105 when cut, coating the tab portions and the cut edges of each strip with waterproofing material, applying granular material to the coated portions and severing each strip transversely into strip shingles.
